(57) **CLAIM**

The ornamental design for an arm sling, as shown and described.

DESCRIPTION

FIG. 1 is a front view of an arm sling, showing my new design;

FIG. 2 is a rear view thereof;

FIG. 3 is a front view of the arm sling of FIG. 1 in a configuration of use;

FIG. 4 is an enlarged view of portion 4 indicated in FIG. 1; FIG. 5 is an enlarged view of portion 5 indicated in FIG. 1; FIG. 6 is an enlarged view of portion 6 indicated in FIG. 2; FIG. 7 is an enlarged view of portion 7 indicated in FIG. 2; and,

FIG. 8 is an enlarged view of portion 8 indicated in FIG. 3. The broken lines illustrating a person in FIG. 3 depict an environment of use that forms no part of the claimed design. The broken lines depict portions of the arm sling that form no part of the claimed design.
